Inventor:

Wm. Lindsey

United States Patent Office.

WILLIAM LINDSEY, OF OBERLIN, OHIO.

Letters Patent No. 63,782, dated April 9, 1867.

IMPROVEMENT IN CATTLE PUMPS.

The Schedule referred to in these Letters Patent and making part of the same.

TO ALL WHOM IT MAY CONCERN:

Be it known that I, W. LINDSEY, of Oberlin, in the county of Lorain, and State of Ohio, have invented certain new and useful improvements in Cattle Pumps; and I do hereby declare that the following is a full and complete description of the construction and operation of the same, reference being had to the accompanying drawings, making a part of this specification, in which—

Figure 1 is a side view of the pump.

Figure 2 is a front view.

Figure 3 is a top view.

Figure 4 is a vertical section.

Like letters of reference refer to like parts in the views.

This apparatus consists of a metallic cylinder, which is constructed in two sections, A B, fig. 1. The upper section is simply a plain cylinder, and about one-third the length of B. In section B is arranged a spiral spring, C, fig. 4, the upper end of which is connected to an adjustable collar or washer, D, fitted to the inside of the cylinder, and in which it moves upward and downward, as will hereafter be shown. The lower end of this spring is attached to the side of the cylinder by the links b, and by the means of which the adjustable collar or washer is forced upward. E is a plunger fitted to the inside of the cylinder, and packed with any suitable material, in order that it may be tight. F is a tube or pipe fastened to the top of the plunger, and which passes through the top and opens on the inside of the plunger with a conical-shaped enlargement, G. I, is a brace surrounding the enlargement G, the top of which is fastened to the pipe, and the bottom spreads out, so as to fill the inside of the piston, as shown in the drawing. J is a sleeve encasing the tube F, the lower end of which is fastened to the top of the plunger, and upon the upper end rest the arms K, fig. 2. To these arms are hinged in any suitable manner the platforms L, one on each side, as indicated. The lower or free end of the platform rests upon the arms M, and upon which they slide on friction-rollers, c, for a purpose as will hereafter be shown. N are standards, between which the pump is placed upon the base O; these standards are connected to the arms K by the links P, and in which the arms slide upward and downward, and thereby guiding and retaining the platform in proper position.

Having thus described the construction of the pump, the operation of the same is as follows: The pump is placed in the well or water so it shall be immersed more or less, according to the depth of the water or the nature of the surrounding ground, or so as to bring the arms M near the ground. When in this position the cattle to be watered walk up the platform to the trough Q, and in so doing their weight depresses the inner ends of the platforms, and these, as above said, being attached to the arms K, and these arms in turn connected to the pipe F, forces the plunger down towards the bottom of the cylinder; this downward action of the piston forces the water up through the pipe F, and from which it flows out of the bent end into the trough above, as the piston or plunger ascends by the reaction of the spring referred to. When relieved from its downward pressure by the cattle moving from the platform, the valve a opens by the outside pressure of the water, and through which it flows and fills the cylinder, and thus supplying it with water as before, and so on alternately, as the piston descends, the valve is closed and the water forced up through the pipe into the troughs, and as the piston rises the valve opens and the water flows in, to be again elevated to the troughs. By the means of suitable pipes connected to the apparatus, water may be conveyed to the house, barn, or other building, or to any adjoining place where the water may be required.

What I claim as my improvement, and desire to secure by Letters Patent, is—

1. The spring C, link b, valve a, and collar D, as arranged in combination with the plunger E, pipe F, and cylinders A B, for the purpose and in the manner as specified.
2. The sleeve J, platforms L, and arms M, as arranged in combination with the pipe F, plunger E, spring C, for the purpose and in the manner as described.
3. Standards N, links P, arms K, and trough Q, as arranged in the manner and for the purpose herein specified.

WM. LINDSEY.
